UNITED STATES PATENT OFFICE.

PHEOLA J. PARSON, OF ARNOLD, KANSAS.

STACK-FORMING TRUCK.

Application filed September 10, 1921. Serial No. 499,808.

To all whom it may concern:

Be it known that I, PHEOLA J. PARSON, a citizen of the United States, residing at Arnold, in the county of Ness and State 5 of Kansas, have invented certain new and useful Improvements in Stack-Forming Trucks, of which the following is a specification, reference being had to the accompanying drawings.

10 This invention relates to stack formers, particularly to that type adapted to trail along beside a harvester such as a header or the like, and has for its object the provision of a novel truck device which carries a rack within which the grain is deposited for forming the stack, this truck being provided with means whereby the completed stack may be moved off and deposited upon the ground at the desired location.

20 An important object is the provision of a device of this character which is provided with novel power operated means for moving the completed stack off of the truck, this means being operable at will.

25 Another object is the provision of a truck device of this character which is provided with peculiar means whereby the stack moving member may be thrown into and out of gear so as to permit turning of the device at the end of a row.

30 A further object is the provision of novel means whereby the movable floor or bottom which supports the stack as it is formed may be swung downwardly to permit moving off of the stack and swung upwardly to be again disposed in receiving position, novel brace means being furthermore provided for holding the movable floor in its normal or elevated position.

40 An additional object is the provision of a device of this character which will be comparatively simple and inexpensive in construction, easy to operate, highly efficient in action, durable in service and a general improvement in the art.

45 With the above and other objects and advantages in view, the invention consists in the details of construction to be hereinafter more fully described and claimed, and illustrated in the accompanying drawings, in which:

Figure 1 is a plan view of the device;

Figure 2 is a side elevation thereof;

50 Figure 3 is a cross sectional view taken 55 through the front axle;

Figure 4 is a longitudinal sectional view; Figure 5 is a rear view;

Figures 6, 7 and 8 are detail views.

Referring more particularly to the drawings, I have shown my device as comprising an elongated rectangular open frame 10 which may be formed of suitable timbers or angle iron of any preferred cross sectional configuration. At its rear end this frame is supported upon small wheels or rollers 11 which are of just sufficient height to prevent the rear end of the frame from striking the ground or any ordinary obstruction thereon. At its forward end this frame is provided with a fifth wheel construction 12 which is supported upon a front axle 13 which carries wheels 14 which are of considerably greater diameter than the wheels 11 so that the frame will be always rearwardly and downwardly inclined. The front axle 13 has the usual tongue 15 connected therewith and the usual hounds or braces 16. Carried by the front wheels are gears 17 for a purpose to be described.

Disposed within the rectangular frame 10 is a movable floor or bottom 18 which has its rear end extending beyond the frame 10 and which has its forward end pivotally mounted upon shafts 19 which are journaled through or upon the sides of the frame 10. Located upon these shafts are sprockets 20 about which are trained chains 21 which extend longitudinally around the floor 18 and which are trained about guide rollers or sprockets 22 at the rear end of the floor. These chains 21 are connected by an endless apron 23 which may or may not be provided with slats as preferred. Connected with the outer ends of the shafts 19 by universal joints 24 are swingingly mounted shafts 25 which carry gears 26 adapted to be brought into mesh with the gears 17 associated with the front wheels for the purpose of effecting rotation of the shafts 19 for driving the conveyor apron 100 when desired.

Mounted upon the rear ends of the side bars of the frame 10 are upwardly extending brackets 27 which are slotted and which have their inner edges formed as racks 28. Journaled upon the floor 18 are pinions 29 meshing with these racks and carrying handles 30 whereby they may be rotated for the purpose of raising or lowering the floor 18 with respect to the frame.

In order to provide means for rigidly supporting the floor 18 in its normal or horizontal position, I provide a plurality of braces 31 which are hinged with respect 5 to the floor and which have their lower ends formed as angular feet 32 engageable upon the side bars of the frame 10. All these braces are connected by a longitudinal rod 33 whereby all the braces may be 10 swung simultaneously out of engagement with the frame for permitting the floor 18 to be lowered by the rack and pinion mechanism above described.

The numeral 34 designates the stack 15 forming rack which is mounted upon the frame 10 and which extends upwardly to any desired height and which has its rear end provided with a gate 35 which may be opened when it is desired to deposit a 20 formed stack upon the ground.

Mounted upon the front end of this rack is a suitable seat 36 for the operator and associated with this seat is preferably provided a foot rest 37. Secured at the front 25 end of the frame or upon a bolster which might be interposed between the frame and the axle, are segmental racks 38 with which are associated pivoted levers 39 extending upwardly at opposite sides of the seat with 30 in convenient reach of the operator. Movably mounted upon the sides of the frame by means of bolts 40^a engaging in slots 40^b formed therein are brackets 40 which are connected with the levers 39 by a link and 35 angle lever connection designated broadly by the numeral 41, and which are provided with bearing slots 42 for the jointed shafts 25. The slots 40^b and 42 of the brackets 40 diverge and by reason of this divergence, 40 when the brackets 40 are moved rearwardly upon the frame the shafts 25 are elevated and the gears carried thereby disengaged from the drive gears 17. Movement in the 45 opposite direction will, of course, bring the gears 17 and 26 into engagement.

The operation of the device is as follows: In order to render the device ready for service, the floor 18 is raised in a horizontal position as shown in Figure 2 by means of 50 the rotatable pinions 29 cooperating with the racks 28 and the rods 33 are moved to swing the braces 31 into engagement with the sides of the frame 10. When pressure upon the pinions 29 is relieved, the weight 55 of the floor and associated parts will hold the braces 31 in position so that the floor will be rigidly supported and be capable of sustaining great weight. The device is drawn along the side of the harvester, 60 header or other similar mechanism and grain from the latter is deposited within the rack 34.

Assuming that the stack has been formed, when it is desired to remove it 65 from the device, it is necessary to open the

gate 35 in the rack and to set the conveyor apron in motion. Before setting the conveyor in motion it is, however, necessary to move the rods 33 so as to release the braces 31 from engagement with the frame and this may be easily accomplished if the pinions 29 are rotated slightly to elevate the floor a sufficient extent to relieve the strain upon the braces. The floor is then allowed to descend to its lowermost position and its rear end will almost touch the ground. The operator then moves the levers 39 in the proper direction to move the brackets 40 so as to swing the jointed shafts 25 downwardly for bringing the gears 26 into mesh with the gears 17, after which the levers are locked by means of the usual grip released pawl mechanism cooperating with the segments 38. When the device is then driven, the gears 26 will be driven and this will result in driving of the sprockets 20 and consequent rearward movement of the conveyor apron 23 which will cause the entire stack to pass rearwardly on to the ground. The parts of the truck are then returned to initial position and the device is then again ready for use in forming another stack.

From the foregoing description and a study of the drawings it will be apparent 95 that I have thus provided a comparatively simple and inexpensive truck which is well adapted for use in forming stacks of grain as the latter is cut or harvested, efficient means being provided whereby the finished 100 stacks may be deposited upon the ground in a rapid manner and by the application of power derived from pulling the device over the ground. Owing to the gradual 105 downward and rearward incline of the frame and floor, when the latter is in lowered position, it will be apparent that there is no likelihood of upsetting the stack when depositing it on the ground. It is also to be noted that the novel means for 110 throwing the conveyor device into and out of operation permits the device to be thrown into gear very easily when dumping or unloading of the stack is desired, the gear mechanism being normally inactive so 115 as not to interfere with the necessary turning action or any irregularities in the movement of the front wheels while the device is being loaded. Another noticeable feature 120 is the provision of the novel bracing mechanism which supports the movable floor in horizontal position and with such rigidity that it is capable of sustaining a heavy weight without danger of breakage of any of the parts.

While I have shown and described the preferred embodiment of the invention, it is of course to be readily understood that I reserve the right to make such changes in the form, construction and arrangement 130

of parts as will not depart from the spirit of the invention or the scope of the subjoined claims.

Having thus described my invention, I 5 claim:

1. A stack forming truck comprising a wheel supported frame disposed in rearwardly and downwardly inclined position, a floor pivotally mounted at the forward end 10 of said frame, means for raising and lowering said floor into horizontal or into rearwardly and downwardly inclined position, a conveyor associated with said floor, and drive means for the conveyor.

15. 2. A stack forming truck comprising a wheel supported frame disposed in rearwardly and downwardly inclined position, a floor pivotally mounted at the forward end of said frame, means for raising and lowering said 20 floor into horizontal or into rearwardly and downwardly inclined position, a conveyor associated with said floor, and drive means for the conveyor, comprising jointed shaft members connected with the conveyor to 25 drive the same, gears carried by said jointed shafts, gears associated with the front wheels and engageable by said first named gears, and lever operated means for swinging said jointed shafts to bring the gears 30 into and out of mesh.

3. A stack forming truck comprising an elongated frame, relatively small wheels supporting the rear end thereof, a swingable axle mounted beneath the front end of the 35 frame and carrying wheels of relatively large diameter whereby the frame will be downwardly and rearwardly inclined, a rack extending upwardly from the frame, a floor pivotally mounted within said frame at the 40 forward end thereof, a conveyor movable longitudinally along said floor, means for driving said conveyor at selected times, and means for swinging said floor upwardly and downwardly.

45. 4. A stack forming truck comprising an elongated frame, relatively small wheels supporting the rear end thereof, a swingable axle mounted beneath the front end of the frame and carrying wheels of relatively 50 large diameter whereby the frame will be downwardly and rearwardly inclined, a rack extending upwardly from the frame, a floor pivotally mounted within said frame at the forward end thereof, a conveyor movable longitudinally along said floor, means for 55 driving said conveyor at selected times, and means for swinging said floor upwardly and downwardly, said means comprising upstanding slotted brackets secured at the rear 60 end of the frame and formed at their inner edges with racks, and pinions journaled

upon the floor and meshing with said racks, said pinions having crank handles.

5. A stack forming truck comprising a wheel supported frame extending in rearwardly and downwardly inclined direction, a floor pivoted within said frame at the forward end thereof, a rack carried by the frame, a conveyor movable rearwardly along said floor, means for driving said conveyor 70 at selected times, means for raising and lowering the rear end of the floor, and means for holding said floor normally in its elevated or horizontal position comprising a plurality of brace members pivoted upon the under side of the floor and engageable with the side bars of the frame.

6. A stack forming truck comprising a wheel supported frame extending in rearwardly and downwardly inclined direction, 80 a floor pivoted within said frame at the forward end thereof, a rack carried by the frame, a conveyor movable rearwardly along said floor, means for driving said conveyor at selected times, means for raising and 85 lowering the rear end of the floor, means for holding said floor normally in its elevated or horizontal position comprising a plurality of brace members pivoted upon the under side of the floor and engageable 90 with the side bars of the frame, and longitudinally extending rods connected with all the braces at each side whereby to effect simultaneous movement thereof.

7. A stack forming truck comprising an 95 elongated rectangular frame, relatively small rollers supporting the rear end thereof, a swingable axle supporting the front end of the frame and carrying relatively large wheels whereby the frame will be rearwardly and downwardly inclined, a movably mounted floor within the frame, a conveyor movable rearwardly of said floor, shafts journaled transversely at the forward end of the frame and carrying sprockets for 100 moving the conveyor, shaft members having universal joint connection with the outer ends of said shafts and carrying gears, other gears carried by the front wheels, bracket members movably mounted upon the sides of the frame and having bearings receiving said last named shafts, and a pair of levers movable over segmental racks and connected with the associated brackets whereby to swing said last 115 named shafts for bringing the first named gears selectively into or out of mesh with said last named gears.

In testimony whereof I hereunto affix my signature.

PHEOLA J. PARSON.
